THOMAS J. BARKER AND FRANK L. MILLER, OF ROSEDALE, KANSAS.

JOIST-FORM.

1,253,833.

Specification of Letters Patent. Patented Jan. 15, 1918.

Application filed February 15, 1917. Serial No. 148,849.

To all whom it may concern:

Be it known that we, THOMAS J. BARKER and FRANK L. MILLER, citizens of the United States, residing at Rosedale, in the county of Wyandotte and State of Kansas, have invented a certain new and useful Improvement in Joist-Forms, of which the following is a specification.

Our invention relates to improvements in joist forms.

It relates particularly to joist forms for making concrete joists.

One of the objects of our invention is to provide a joist form, which may be adjustable as to width and height, which, when not in use, may be collapsed, and the parts nested so as to be in compact form for storage or transportation, which may be easily assembled and disassembled, which is cheap to manufacture, which is strong and durable and not liable to get out of repair, and which may be readily removed from its operative position after the material which forms the joist has become sufficiently set.

The novel features of our invention are hereinafter fully described and claimed.

In the accompanying drawing which illustrates the preferred embodiment of our invention,

Figure 1 is a perspective view of our improved joist form, with the end closure removed.

Fig. 2 is an inside elevation of the end closure.

Fig. 3 is an under view of our improved joist form.

Fig. 4 is an outside elevation of the end closure.

Fig. 5 is a perspective view, reduced, of one of the right-angled members and parts connected therewith.

Fig. 6 is a vertical sectional view on the line 6—6 of Fig. 3.

Fig. 7 is a plan view, partly broken away, of a number of our joist forms shown supported on soffit boards.

Fig. 8 is an enlarged cross section on the line 8—8 of Fig. 7.

Similar reference characters designate similar parts in the different views.

1 and 2 designate respectively two substantially right-angled members having horizontal tops which overlap and are ad-

justable toward and from each other, thereby forming an inverted U-shaped form 55 which is extensible as to width.

The sides of the members 1 and 2 are upright and, preferably, have a slight taper to enable their ready removal from the concrete. Said sides are extensible as to height, 60 and for this purpose, there is disposed for this purpose at the inner side of each upright portion or side of each member 1 and 2, an upright plate 3 which is provided at its lower edge with an inwardly extending 65 longitudinal flange 4. Rigidly secured, by soldering, riveting or otherwise, to each plate 3, are two upwardly extending bars 5, which are provided each with a vertical row of holes 6, which are adapted to register 70 with a hole 7, of which two are provided in each upright portion or side of the members 1 and 2. A bolt 8 extends through the hole 7 and through one of the holes 6. On the bolt 8 at the inner side of the plate 5 is 75 mounted a nut 9 which bears against the inner side of the plate 5, Fig. 6.

By changing the bolts 8 to different holes 6, the height of the form may be varied.

For holding the members 1 and 2 in the 80 positions to which they are adjusted, the following described mechanism may be employed.

A pair of brace members, preferably comprising channelled members, 10 and 11, are 85 pivoted on vertical axes to the under side of the top of the member 1 and to two brackets 12 respectively, which are secured to the inner side of the upright portion of said member.

The brace members 10 and 11 are arranged so as to be swung from a longitudinal position to a horizontal transverse position as shown in Figs. 1 and 3.

The member 11 is of sufficient width to 95 embrace the member 10 when the two are swung to the longitudinal position shown in Fig. 5.

Two similar brace members 10 and 11 are pivoted in a like manner to the inner side of 100 the upright portion of the member 2. The member 11 of the member 2 is of a width sufficient to enable it to embrace the member 10, which is pivoted to the member 1, as shown in Fig. 1, when the brace members are 105 swung to the transverse position. In like

manner, the brace member 11 of the member 1 is adapted to embrace and telescopically engage the member 10 which is pivoted to the member 2.

5 To the under side of the top of the member 2 are secured downwardly extending stops 13 and 14 for engaging the members 11 to limit their outward swinging movement.

10 For holding said brace members in the transverse position, we provide a longitudinal central brace member 15, the ends of which are adapted to enter the two brace members 10 at right angles thereto and between the flanges thereof.

Two securing devices comprising, preferably, two nails 16, are insertible through holes 17, of which a longitudinal row is provided in the lower flange of each member 10

20 and 11. Said holes 17 are so arranged that when the members 1 and 2 are adjusted to the proper position, the nails 16 may be inserted through holes 17 which are in register with each other and the nails driven into the wooden brace member 15, as shown in Fig. 6.

For closing the end of the form, a closure is provided which is extensible as to width and height. Referring particularly to Figs.

30 2 and 4, 18 designates a plate disposed vertically and provided at its upper and outer side edges with inwardly extending flanges 19 adapted to embrace the outer sides of the inverted U-shaped form.

35 A similar vertically disposed plate 20 having inwardly turned flanges 21 adapted to embrace the top and one side of the inverted U-shaped form is horizontally slidable with respect to the plate 18 to which it is adapted 40 to be clamped by means of a horizontal bolt 22 which extends through a hole in the plate 20 and through a horizontal slot 23 in the plate 18. On the inner side of the bolt 22 and bearing against the inner side of the plate 18 is a nut 24. Vertically adjustable in the plates 18 and 20, are two vertical plates 25 and 26, each of which is provided with a vertical row of holes 27, each of which is adapted to register with a hole 50 provided in each of the plates 18 and 20. Two bolts 28 are respectively mounted in said holes in the plates 18 and 20, and extend each through one of the holes 27. Respectively mounted on the bolts 28 are nuts 29, 55 which respectively bear against the inner sides of the plates 25 and 26.

The plate 26 is provided with a hole through which extends a horizontal bolt 30, which also extends through a horizontal slot 60 31 in the plate 18. On the bolt 30 is mounted a nut 32 which bears against the inner side of the plate 18.

By properly adjusting the bolts 22, 28 and 65 30, the closure may be adjusted to snugly fit over the outside and one end of the inverted

U-shaped form, as shown in Figs. 3 and 6. The lower edge of the plate 25 is provided with an inwardly extending flange 33. The outer side edges of the plates 25 and 26 are provided with inwardly turned flanges 34 70 adapted to respectively embrace opposite sides of the inverted U-shaped form.

One end of said U-shaped form is slightly smaller than the other end, so that such smaller end may be fitted within the larger 75 end of an adjacent form, as shown in Fig. 7, when a number of these forms are fitted together end to end.

In the operation of our invention, a series of horizontal longitudinal and transverse 80 soffit boards 35 are erected. Secured to the edges of said soffit boards 35 and extending above the upper surfaces thereof are detachable blocks 36, Figs. 7 and 8. Upon the soffit boards 35 are placed inverted U-shaped 85 forms with the flanges 4 resting upon the boards 35 with their inner edges disposed against the blocks 36 which form stops for holding the forms from lateral movement. Nails 37 are inserted through holes provided 90 in the flanges 4 and driven into the adjacent soffit boards 35, for holding the form members 1 and 2 from longitudinal movement, see Fig. 8.

The end closures are then applied to the 95 opposite ends respectively of the series of forms which have been fitted together, as shown in Fig. 7, with the flanges 33 of said closures having their inner edges bearing against the adjacent stock blocks 36, with 100 which the inner edges of the transverse soffit boards 35 are provided.

The concrete is then poured upon the soffit boards 35 and the assembled U-shaped forms, covering the latter to the required 105 depth and permitted to stand until sufficiently hardened, after which the blocks 36 are removed from the soffit boards 35, and the nails 16 and 37 withdrawn. The brace members 10 and 11, upon the removal of the 110 brace members 15, may then be swung to the longitudinal position shown in Fig. 5, after which the members 1 and 2 may be removed by inward withdrawal. Upon loosening the nuts 24, 29 and 32, the end closures may be 115 also removed by inward withdrawal.

We do not limit our invention to the structure shown and described, as modifications, within the scope of the appended claims, may be made without departing from the 120 spirit of our invention.

What we claim is:—

1. In a joist form, a substantially right-angled member having a horizontal top and an upright side, and a brace member pivoted 125 to the inner side of said right-angled member and adapted to be swung from a longitudinal collapsed position to a horizontal transverse position relatively to said right-angled member and provided with a longi- 130

tudinal row of holes adapted to receive a securing device.

2. In a joist form, a substantially right-angled member having a horizontal top and an upright side, the latter having at its lower edge an inwardly turned longitudinal flange, and a brace member pivoted to the inner side of said right-angled member and adapted to be swung from a longitudinal collapsed position to a horizontal transverse position relatively to said right-angled member and provided with a longitudinal row of holes adapted to receive a securing device.

15 3. In a joist form, a substantially right-angled member having a horizontal top and provided with an upright substantially vertically extensible side, the lower edge of which is provided with an inwardly turned longitudinal flange, and a brace member pivoted to the inner side of said right-angled member and adapted to be swung from a longitudinal collapsed position to a horizontal transverse position relatively to said right-angled member.

4. In a joist form, a substantially right-angled member having a horizontal top and provided with an upright substantially vertically extensible side, the lower edge of which is provided with an inwardly turned longitudinal flange, and a brace member pivoted to the inner side of said right-angled member and adapted to be swung from a longitudinal collapsed position to a horizontal transverse position relatively to said right-angled member and having a longitudinal row of holes adapted to receive a securing device.

5. In a joist form, a substantially right-angled member having a horizontal top and an upright side, and two brace members pivoted to the inner side thereof so as to be swung from a longitudinal position to a horizontal transverse position, each brace member having a longitudinal row of holes adapted to receive a securing device.

6. In a joist form, a substantially right-angled member having a horizontal top and an upright side, and two channel brace members pivoted to the inner side thereof so as to be swung from a horizontal transverse position to a longitudinal position, one of the brace members having a channel sufficiently wide to receive the other brace members when the brace members are in the longitudinal position.

7. In a joist form, a substantially right-angled member having a horizontal top and an upright side, and two channel brace members pivoted to the inner side thereof so as to be swung from a horizontal transverse position to a longitudinal position, one of the brace members having a width such that it will embrace the other brace member when the brace members are in the longi-

tudinal position, each brace member having a longitudinal row of holes adapted to receive a securing device.

8. In a joist form, a substantially right-angled member having a horizontal top and an upright side, the latter having at its lower edge an inwardly turned longitudinal flange, and two channel brace members pivoted to the inner side of said right-angled member, one channel member having a width which permits it to embrace the other channel member when they are in the longitudinal position.

9. In a joist form, a substantially right-angled member having a horizontal top and an upright side, the latter having at its lower edge an inwardly turned longitudinal flange, said side being substantially vertically extensible, and two channel brace members pivoted to the inner side of said right-angled member, one channel member having a width which permits it to embrace the other channel member when they are in the longitudinal position, each of said channel members having a longitudinal row of holes adapted to receive a securing device.

10. In a joist form, a substantially right-angled member having a horizontal top and an upright side, said member having on its inner side a stop, and a brace member pivoted to the inner side of said right-angled member and adapted to be swung from a horizontal transverse position against said stop to a longitudinal position.

11. In a joist form, two substantially right-angled members having overlapping horizontal tops and upright sides, two brace members respectively pivoted to the inner sides of said right-angled members so as to swing from a longitudinal position to horizontal transverse positions, the right angled members being adjustable toward and from each other, and means for releasably securing together said brace members.

12. In a joist form, two substantially right-angled members having overlapping horizontal tops and upright sides and adjustable toward and from each other, two channel brace members respectively pivoted to said right-angled members so as to be swung from a longitudinal position to a horizontal transverse position and in the latter position being adapted to telescopingly engage each other, and releasable means for securing the brace members to each other in said last named position.

13. In a joist form, two substantially right angled members having overlapping tops and upright sides and adjustable toward and from each other, two pairs of brace members pivoted one pair to the inner side of each right-angled member so as to be swung from a longitudinal position to a horizontal transverse position and in the latter position being adapted for engagement

with the adjacent brace member of the other pair, a longitudinal brace member, and means for releasably securing the longitudinal brace member to the two pairs of brace members so as to hold the latter in the transverse position.

14. In a joist form, two substantially right-angled members adjustable toward and from each other, two pairs of brace members respectively pivoted to the inner sides of said right-angled members so as to be swung from a longitudinal position to a horizontal transverse position, each brace member being provided with a longitudinal 15 row of holes adapted to register with the holes of the adjacent brace member of the other pair, a longitudinal brace member, and two securing devices adapted respectively to be inserted through the holes of the brace 20 members which are in register with each other and to engage said longitudinal brace member when the first named brace members are in the transverse position.

15. In a joist form, horizontal supports, 25 stops secured thereto and extending above the upper surfaces thereof, two substantially right-angled members having overlapping horizontal tops and upright sides and adjustable toward and from each other, each side 30 having at its lower edge and inwardly extending longitudinal flange, said sides resting respectively on said supports, and the inner edges of said flanges respectively engaging said stops, and releasable means for 35 securing said right-angled members in the positions to which they may be adjusted relatively to each other.

16. In a joist form, horizontal supports, 40 stops secured thereto and extending above the upper surfaces thereof, two substantially right-angled members having overlapping

horizontal tops and upright sides and adjustable toward and from each other, each side having at its lower edge an inwardly extending longitudinal flange having its inner 45 edge bearing against one of said stops, two brace members respectively pivoted to the inner sides of said right-angled members so as to be swung from a longitudinal to a horizontal transverse position, and means for releasably securing said brace members to each other in said transverse position.

17. In a joist form, two right-angled members having overlapping tops and upright sides and adjustable toward and from each other, releasable bracing means connecting said right-angled members, said sides of said members being substantially vertically extensible, and a closure extensible as to height and width and having flanged 60 edges respectively embracing the outer sides of said right-angled members.

18. In a joist form, horizontal supports stops secured thereto, and extending above the upper surfaces thereof, two substantially 65 right-angled members having overlapping horizontal tops and upright sides and adjustable toward and from each other, each side having at its lower edge an inwardly extending longitudinal flange having its inner 70 edge bearing against one of said stops, releasable bracing means connecting said right-angled members, and an end closure extensible as to width and embracing the outer sides of said right-angled members 75 and having at its lower edge an inwardly extending flange which bears against one of said stops.

In testimony whereof we have signed our names to this specification.

THOMAS J. BARKER.
FRANK L. MILLER.
